US0D1104747S

(12) **United States Design Patent** (10) **Patent No.:** **US D1,104,747 S**
(45) **Date of Patent:** **** Dec. 9, 2025**

(54) **MEDICINE CONTAINER**

(71) Applicant: **Cabinet Health P.B.C.**, Brooklyn, NY (US)

(72) Inventors: **Russell Eliot Gong**, Weston, CT (US); **Achal Apurva Patel**, Brooklyn, NY (US)

(73) Assignee: **Cabinet Health P.B.C.**, Brooklyn, NY (US)

(**) Term: **15 Years**

(21) Appl. No.: **29/909,370**

(22) Filed: **Aug. 4, 2023**

Related U.S. Application Data

(63) Continuation of application No. 29/783,354, filed on May 12, 2021, now Pat. No. Des. 994,317.

(57) **CLAIM**

The ornamental design for a medicine container as shown and described.

DESCRIPTION

FIG. 1 is a first perspective view of a medicine container showing our new design;

FIG. 2 is a second perspective view thereof;

FIG. 3 is a front view thereof;

FIG. 4 is a side view thereof;

FIG. 5 is a rear view thereof;

FIG. 6 is a side view of the opposite side of FIG. 4;

FIG. 7 is a top view thereof; and,

FIG. 8 is a bottom view thereof.

The broken lines shown in the drawings illustrate portions of a medicine container that form no part of the claimed design.

1 Claim, 8 Drawing Sheets
